By E. E. Vrooman, his Attorney.

UNITED STATES PATENT OFFICE.

JOHN VICTOR VICKSELL, OF MEDIAPOLIS, IOWA.

LIFTING AND LOWERING APPARATUS.

No. 894,923.

Specification of Letters Patent.

Patented Aug. 4, 1908.

Application filed January 25, 1908. Serial No. 412,619.

To all whom it may concern:

Be it known that I, JOHN VICTOR VICKSELL, a citizen of the United States, residing at Mediapolis, in the county of Des Moines 5 and State of Iowa, have invented certain new and useful Improvements in Lifting and Lowering Apparatus, of which the following is a specification, reference being had therein to the accompanying drawing.

10 This invention relates to an apparatus for raising and lowering pumps, and has for its object the provision of means for facilitating the hoisting or raising of a pump out of a well or the replacing or adjustment thereof 15 in the same.

Another object of the invention is the construction of a pump raising and lowering apparatus, which comprises a minimum 20 number of parts, is comparatively simple to operate, and inexpensive to manufacture.

With these and other objects in view, the invention consists of certain novel constructions, combinations, and arrangements of parts, as will be hereinafter fully described 25 and claimed.

In the drawings: Figure 1 is a perspective view of an apparatus constructed in accordance with the present invention. Fig. 2 is a fragmentary, top plan view of the structure 30 depicted in Fig. 1. Fig. 3 is a fragmentary view, in side elevation, of the apparatus depicted in Fig. 1. Fig. 4 is a fragmentary, sectional view of the clamp-device. Fig. 5 is a plan view of one of the grapples.

35 Referring to the drawings by numerals, 1 designates a platform provided with a bifurcated portion 2 formed in its front end, between the sides of which the pump or tube 3 is positioned, when the apparatus is in operation. A vertical standard 4 is positioned upon the platform 1, and is seated in a bracket 5; the bracket 5 comprises a hollow body 6 and outwardly-extending feet or flanges 7. The feet or flanges 7 are secured 40 to the platform, and as the standard 4 is secured within the hollow body of the bracket 5, said platform and standard are fixedly secured together. A vertical bracket 8, provided with parallel, vertical end-portions 9, is fixedly secured, at its lower end, by 45 any suitable fastening means, as for instance, bolt 10, to the standard 4; and its upper, vertical end 9 is apertured for receiving a horizontal bolt or shaft 11, which bolt or shaft 11 is provided with an outer, bifurcated end 12.

Locking nuts 13 are, preferably, positioned

upon opposite sides of the standard 4, and are threaded upon the bolt and shaft 11 for securing said shaft in an adjusted position upon the standard 4.

60 A lever 14 is pivotally mounted upon the bolt 11 between the bifurcated end 12 and the vertical bracket 8. The lever 14 is provided upon opposite sides of said bolt 11 with a plurality of apertures 15. In one of the apertures upon each side of the bolt or supporting shaft 11 is positioned, preferably, a chain 16, to the lower end of which are attached a grapple 17. Each grapple 17 comprises a grip portion or body 18 having 65 an apertured extension 19; a chain 16 being positioned in the aperture or portion 19. The leverage can be increased or decreased by positioning the chains 16, constituting connecting means, in different apertures in 70 the lever at the side of the bolt or shaft 11.

75 The rod-supporting device of my apparatus comprises a bolt or supporting-member 20, upon which is pivotally mounted the eye or lower apertured-end 21 of the pivotally-mounted bracket 22. The bracket 22 is provided with a vertical body terminating at its upper end in a horizontal extension 23, which extension 23 is provided, at its outer end, with a vertical extension or lug 24. To 80 the horizontal portion 23, any suitable fastening means may be attached for securing the pump-rod in a raised or adjusted position, preparatory to joining or connecting its lower ends with another section or with an 85 additional piece of the rod. When the apparatus is not in use, the pivotally-mounted bracket 22 can be swung rearward, so as to place the horizontal portion 23 below the pivot, constituted by the bolt 20. The forward pivotal movement of the bracket 22 is 90 limited by a pin or lateral, horizontal projection 25 secured to the same side of the standard 4, upon which the extended end of the bolt 20 projects; the pin or stop 25 is 95 placed near the front end of said face for permitting the bracket to swing slightly forward and be retained in said position when the apparatus is in operation.

100 The clamp-device comprises a primary jaw 26 and an auxiliary jaw 27. The jaws 26 and 27 are, preferably, connected at their rear end by a bolt 28, said jaws being placed in a horizontal position for permitting their roughened or toothed portions 29 to grip the 105 pipe or pump 3. The primary jaw 26 is provided with a tongue or tenon 30, which ex-

tends into the bifurcated end of the auxiliary jaw 27. A suitable fastening member, as for instance, bolts 31, extends through the auxiliary jaw 27 and into the platform 1, thereby securing jaw 27 to said platform and preventing pivotal movement thereof, although the primary jaw 26 is pivotally mounted upon said platform and the auxiliary jaws. The auxiliary jaw 26 is provided with a vertical aperture 32, and with a thumb-bolt or set-screw 33. The thumb-bolt or set screw 33 has its inner end (Fig. 4) extending into the vertical aperture 32. An auxiliary lever 34 is pivotally mounted, at 35, upon the front end of the auxiliary jaw 27. The lever is adapted to be swung in a vertical plane for actuating the link 36, which link is pivotally connected to said lever, at 37. The lever 34 is provided with a 20 grip or foot-engaging portion 38, disposed, preferably, at right-angles to the body portion of the same. It will be obvious that upon the operator engaging the foot-portion 38 and swinging the lever outward and downward, the link 36 will be drawn towards the auxiliary jaw 27, and thereby causing or permitting jaw 26 to be closed upon the pipe or pump. The link 36 is provided with an elongated, hollow body, and with an apertured end 39 into which is threaded the angle-bolt 40. The link 36 has, at its opposite end, a flat extension or lip 41, through which the rivet or fastening means 37 extends. The angle-bolt or hook 40 is provided with a vertical portion 42, which vertical portion is provided with a notch or cut-out portion 43, into which the inner end of the thumb-bolt or set-screw extends for holding said hook or angle-bolt and link connected to the primary jaw 26. If it is desired to disconnect the link and the angle-bolt or hook 40 from the primary jaw 26, it is only necessary to thread the bolt or set-screw 33 outward, so that the angle-bolt or hook 40 can be raised from its engagement with the primary jaw.

When the apparatus is to be employed for lifting or lowering a pump, it is only necessary to detach the angle-bolt or hook 40 from the primary jaw and insert said pipe or pump between the bifurcated sides of the platform, causing the jaws to be placed upon opposite sides of the pipe. Then the operator can place the vertical portion 42 of the hook or angle-bolt 40 in the aperture 3 of the primary jaw and fasten the same therein by means of the set-screw 33. Then the operator should swing the lever 14 upon the supporting-shaft or bolt 11, after the grapples 17 have been placed upon the pump or pipe, and as the lever is swung, the grapples will alternately grip the pipe or pump and lift the same. If it is desired to hold the pipe or pump in an adjusted position, all that is necessary is for the operator to place his foot

upon the portion 38 or upon the body portion of the auxiliary lever and swing the same downward, thereby causing the jaws to grip the pipe tightly. Any suitable fastening means can be employed for attaching the pump-rod to the pivoted bracket 22, as before stated. 70

It is to be noted that I have provided a very efficient structure for raising and lowering the pumps or device, and also have provided a small foot-actuated clamp-device for holding the pump after the grapple-device has been employed for lifting the same. When it is desired to lower a pump or pipe, the same is placed in substantially the same position illustrated in Fig. 1, and by pressing downward upon the lever 34, the pipe or pump can be gripped during the placing of the grapples upon the pipe or pump, prior to the loosening of the pressure upon the lever 34; then the pipe can be lowered the distance allowed by the slack in the chain or connecting means 16. The positioning of the grapples higher up on the pipe or pump, each succeeding time, will permit the pump or pipe to 80 be quickly lowered into the well. 85

What I claim is:

1. In an apparatus of the class described, the combination with a support, of a pair of jaws carried by said support, one of said jaws provided with an aperture, lever means carried by said support, and means pivotally connected to said lever means and positioned in the aperture of said jaw for drawing the last-mentioned jaw towards the other jaw 100 when said lever means is swung.

2. In an apparatus of the class described, the combination with a support, of jaws carried by said support, one jaw being capable of movement relative to the other jaw, a lever pivotally connected to one jaw, a link pivotally connected at one end to said lever, said link provided with a hollow body, a hook threaded through one end of said link and having a portion extending into said hollow body, said hook having a portion extending into one jaw, and means fastening the extended portion of the hook in said jaw. 105 110

3. In an apparatus of the class described, the combination with a support, of a stationary jaw carried by said support, of a movable jaw co-operating with said stationary jaw, said movable jaw provided with an aperture, a hook extending into said aperture, a thumb-bolt or set-screw threaded into said jaw and 115 120 into engagement with said hook for preventing the same from being displaced off of said jaw, and means engaging said hook for drawing together or moving the jaws apart.

4. In an apparatus of the class described, the combination with a platform or support, of a clamp-device carried by said platform, said clamp-device comprising jaws movably connected, a link provided with an adjustable hook, at one end, the hook extending 125 130

into one of said jaws, and means carried by the other jaw and being capable of actuating said link for adjusting the jaw carrying the link.

- 5 5. In an apparatus of the class described, the combination with a platform, of a clamp-device carried by said platform, said clamp-device comprising a pair of jaws, a lever secured contiguously to one of said jaws, a hook 10 provided with a portion extending into the other jaw, said hook provided with a notch, fastening means extending through a portion of said jaw and engaging said notch for securing said hook upon said jaw, and means connecting said hook and lever, whereby when said lever is swung, the jaw carrying the hook will be adjusted.

6. In an apparatus of the class described, the combination with a support, of a pair of jaws carried by said support, lever means 20 pivotally secured to one of said jaws, adjustable connecting means secured to said lever means, said connecting means provided with a hook detachably positioned in one of said jaws, and said lever means adapted to draw 25 the connecting means towards one jaw for moving one jaw towards the other jaw.

In testimony whereof I hereunto affix my signature in presence of two witnesses.

JOHN VICTOR VICKSELL.

Witnesses:

C. H. BECKMAN,
JOE BECKMAN.
